Patented Sept. 24, 1957

181,042

CARRYING CASE

Raymond E. Covington, Pasadena, Calif.
Application August 6, 1956, Serial No. 42,526

Term of patent 14 years

(Cl. D87—5)

Fig. 1 is a side elevational view of a carrying case showing my new design;

Fig. 2 is a front elevational view thereof;

Fig. 3 is a top plan view thereof;

Fig. 4 is a rear elevational view thereof;

Fig. 5 is a sectional view thereof, taken on line 5—5, Fig. 2 and looking in the direction of the arrows;

Fig. 6 is a sectional view thereof, taken on line 6—6, Fig. 1 and looking in the direction of the arrows; and

Fig. 7 is a perspective view of a carrying case showing my new design, and with the cover moved to open position to receive a bowling ball which the case is adapted to receive.

I claim:

The ornamental design for a carrying case, as shown and described.
